UNITED STATES PATENT OFFICE.

JOHN PAUL SATTERLEE, OF KLAMATH FALLS, OREGON.

AUDITORIUM, ASSEMBLY-ROOM, OR THEATER CHAIR OR BENCH.

1,352,415.

Specification of Letters Patent. Patented Sept. 7, 1920.

Application filed April 24, 1919. Serial No. 292,521.

To all whom it may concern:

Be it known that I, JOHN PAUL SATTERLEE, a citizen of the United States, residing at Klamath Falls, in the county of Klamath, 5 State of Oregon, have invented new and useful Auditorium, Assembly-Room, or Theater Chairs or Benches, of which the following is a specification.

My invention relates to improvements on 10 an original mechanical combination as designed and applied to any conventional or standard form of auditorium or assembly room or theater chair, and the objects of my improvements and inventions are:

15 1. To construct a retracting, suspended, gravity operated chair, seat or bench which will permit by the action of seat occupant, of increased space being formed at will between him and other objects or chairs in 20 front and thus permit freer passage through wider aisle to any passer-by, without the necessity of the seat occupant rising.

2. To afford a more rigid and stronger type of chair by placing a through rod in 25 the standards of said chair.

3. To afford a stronger seat anchorage by supporting the same on said through rod and also on two hinges thereby making four supports.

30 4. To bring about the locking and holding of all movable parts of the chair when the seat is thrown up in vertical position.

I attain these objects by the mechanism illustrated in the following drawings in 35 which—

Figure 1 is a side view of chair, the nearest standard being removed and front half of exposed support panel broken to show interior.

40 Fig. 2 is a front-rear view with half vertical section at mid-point of back view at right.

Similar letters refer to similar parts throughout the several views.

45 The standards S S, the back, the seat G with ribs M M underneath and the supporting side panels F F, constitute the principal parts of the chair. The occupant seating himself on seat G is in a normal resting 50 position, the weight of his body being partly carried by the fixed through rod B to standards, and partly by hinge bolts H H in side panels F F. (In the drawing these bolts being in line with rod B, do not show 55 separately). The side panels are held up by anchorages r r of hangers R R on the

chair standards. Movement of the front of the seat G down or out of place is restrained by stops x on inside of side panels where ribs M M under the seat strike them. Supporting side panels F F by impinging on fixed rod B, with slots of proper depth, lock seat G and also the side panels from moving up or down and serve as a stop for side panels F F to limit the forward motion thereof.

Desiring to retract the chair, the occupant places feet at K, either on floor or over cleat K, and by a rearward motion of the body pushes the chair seat as well as the 70 supporting side panels and back toward the rear to a point determined by limits of grooves g g which move with the seat over fixed bolt B. This action is brought about by hangers R R swinging about anchorages r r, carrying supporting side panels F F to the rear, also elevating and moving rearwardly points o o on the side panels in an arc of a radius equaling the length of hangers R R which move about centers r r. At 75 the same time the seat moving back on bolt B is retracted and elevated an equal amount. Gravity tends to act and move seat G forward again on inclined grooves g g, and keep it there. When the chair is retracted, a clear 80 space in front of occupant of width equal to length of grooves g g is gained. The action of spring Y fastened to hangers R R and through rod B, also assists the seat with its attached side panels to return, and 85 takes up any indirection of movement on the part of seat G on grooves g g through which the through rod B passes.

The chair being retracted with seat and occupant to the rear, allows clear space in 95 front with wider aisles, and it is only necessary for the occupant to relieve the backward pressure on the chair, when gravity returns the seat to normal position together with the assistance of the spring which resists a decided effort on the part of occupant to move it from normal position.

100 The swinging action of hangers R R may be maintained in the same vertical plane by rolling checks between supporting side panels F F, and standards S S, while the travel of seat G on grooves g g, is controlled by collars C C, on fixed through rod B placed at proper distances apart to retain ribs M M in a correct forward and back line. The movement of supporting side panels F F at their 105 upper edges is approximately in a straight 110

rising line backward, and these may be covered by a cap or hood cover Z which would protect the clothes of occupant from becoming caught as side panels F F move backward and forward, and also by containing and checking side panels F F, would tend to keep the action of the chair in line.

To lock and hold all movable parts of the chair when the seat G is thrown up in clear about hinge bolts H H, circular groove g g is made in ribs M M, which as seat G is revolved about hinge bolts H H, moves on the through rod B locking the seat back and panels in forward position.

15 The following is claimed:

In a chair of the class described, a pair of supporting standards, side panels, links pivotally connected at their lower ends to the side panels and at their upper ends to the

supporting standards; a back, a seat, said seat being pivotally connected to said side panels, side members carried by said seat and having angularly disposed slots therein, one of said slots being arcuate for vertical movement of the seat about its pivot; 25 a bolt connecting the side standards and passing through said slots so that engagement between the bolt and slots will allow the seat to move rearwardly or upwardly, and a retractile spring connected to the 30 links and to said bolt to cause the seat to resume a normal position when moved therefrom.

JOHN PAUL SATTERLEE.
